United States Patent Office

Des. 181,993

Patented Jan. 28, 1958

181,993

MAIL BOX OR THE LIKE

Leonard F. Moran, Santa Monica, Calif.

Application July 5, 1956, Serial No. 42,148

Term of patent 7 years

(Cl. D74—9)

FIG. 1

FIG. 2

FIG. 3

FIG. 4

Fig. 1 is a front perspective view of a mail box showing my new design;

Fig. 2 is a similar perspective view thereof as it appears in expanded position;

Fig. 3 is a rear perspective view of the mail box; and,

Fig. 4 is a similar rear perspective view thereof as it appears in expanded position.

The opposite side portions not visible in the various perspective views are identical to the visible side portions.

I claim:

The ornamental design for a mail box or the like, as shown and described.
